PROCESS FOR TREATING PETROLEUM OIL

Carbon P. Dubbs, Wilmette, Ill., assignor to Universal Oil Products Company, Chicago, Ill., a corporation of South Dakota

Application July 31, 1922, Serial No. 578,704
Renewed July 11, 1934

4 Claims. (Cl. 196—48)

This invention relates to a process and apparatus for treating petroleum oil and refers more particularly to a continuous cracking process in which the oil is converted from relatively high boiling point products to lower boiling point oils.

Among the salient objects of the invention are to provide a process whereby the volume of oil being treated remains constant while the amount of raw oil, the cracking of the oil, the amount of gasoline, and the amount of pressure distillate can be varied.

The necessity of cracking petroleum of high boiling points into low boiling points such as gasoline is becoming more acute owing to the demand for gasoline rapidly increasing. In cracking high boiling point products into the low boiling point products there is necessarily produced carbon in more or less proportion to the amount of the high boiling point petroleum cracked.

Where the cracking of petroleum is carried on in a shell still, the carbon produced progressively increases as the cracking proceeds, such carbon being retained in the still, while the amount of oil in the still is progressively decreased.

In the normal operation of cracking oil in a shell still the low boiling point products produced known as gasoline are contained in what is commonly designated as a pressure distillate. This pressure distillate is that distillate from the still charge which contains what is known as gasoline, kerosene, and certain additional heavier ends. For illustration, the pressure distillate produced contains 50% of gasoline distilling between 100 and 437° F. and 50% consisting of kerosene and oils having higher boiling points. The pressure distillate represents 60% of the total oil charged into the still, and the residuum representing 40 percent of the charging stock. It will be understood that these percentages both as to total percent distillate, its gasoline content, etc., will vary considerably from this according to the character of the oil.

In the operation of a shell still the oil is progressively heated throughout the process while maintained under the desired pressure. Therefore, the first one per cent of pressure distillate distilled off represents one per cent of the total charge; the second per cent of the original charge distilled over represents 1.01% of the oil remaining while the third per cent distilled off of the original charge represents 1.02% of the oil remaining in the still and the process is progressive in this respect, showing that the conditions are not constant, but progressively change, and as

the carbon from all these per cents distilled off is accumulated in the still and is contained in the progressively decreasing amount of oil remaining in the still, it is evident that this process involves a condition that is constantly progressing towards conditions detrimental to the continued carrying on of the process and its operation, therefore, is limited.

It is evident that the oil maintained at the temperature necessary to crack it is very thin and hence limited in its ability to carry carbon in suspension, therefore, it very quickly reaches a point at which the carbon formed in the cracking starts to deposit on the steel plates of the still. This carbon being a very efficient insulating material prevents the heat of the furnace being readily transmitted to the oil contained in the still with the result that the metal at that spot becomes overheated.

This condition applies to any apparatus whether the external heat is applied to the still proper or to tubes through which the oil circulates when the total residuum is retained in the cracking unit. It also applies to cases where additional raw oil is fed to the cracking unit.

When attempts are made to withdraw part of the residuum from the unit it is found that the oil so withdrawn frequently contains a greater per cent of low boiling point products than the original charging stock.

One object of my invention is to overcome the foregoing objections by providing a process whereby the volume of hydrocarbon material treated remains constant while the amount of raw oil fed into the system, the amount of pressure distillate produced and the amount of gasoline produced can be varied.

The single figure is a diagrammatic side elevational view of the apparatus.

The raw oil is drawn from any suitable source not shown and by means of a pump is forced through line 1 through valve 2, valve 3 being closed, through line 4 into the cracking coil 5. As the oil passes through this cracking coil it is heated by the furnace 6. The heat passes from the furnace 6 through the ports 7 into the top part of the chamber containing the cracking tubes and passes downward around the tubes to a flue not shown. The oil passing through the coils is raised to a conversion temperature and then passes through line 8 into expansion chamber 9.

The process is not confined to any particular kind of apparatus and while the oil is shown as entering the side of the expansion chamber

near the bottom and discharges near the top as shown, it may enter at any convenient point of said expansion chamber.

The vapors from the expansion chamber pass 5 through line 10 into the bottom of the dephlegmator. The dephlegmator contains pans or any other suitable arrangement for accomplishing the result which is later described. More or less of the vapors while ascending through the dephlegmator are condensed and are dropped back 10 and pass to dephlegmator leg 11, through pipe 12, back to the cracking coils 5. The vapors remaining in the dephlegmator pass through the line 13, into final condenser 14 which may be 15 of any convenient type and from there through line 15, into receiver tank 16. During this operation no pressure is kept on the apparatus and it is continued until a small amount of distillate has accumulated in tank 16 by which 20 means practically all the air is thus removed from the interior of the different parts of the apparatus, at which time the valve 2 is closed and the valve 3 opened and the raw oil fed through line 17 into the dephlegmator through line 18. 25 Attention is called to the fact that this line 18 extends part of the way down into the dephlegmator and this is one of the essential parts of my invention which I will describe later.

When the apparatus is brought to the pressure 30 it is desired to operate at then the surplus incondensable gas is taken off through line 19, either continuously or intermittently, being controlled by valve 20. This may be a hand control valve or an automatically operated valve. 35 The pressure distillate flowing into the pressure distillate tank 16 is drawn off through line 21 controlled by valve 22 to any suitable storage. The amount of liquid in the receiving tank 16 is ascertained through a gauge glass or any other convenient means well known to the art. The 40 raw oil, as will be noted, is discharged into the dephlegmator at a point which will bring the vapors in contact with this raw oil so as to obtain the highest efficiency of transfer of heat from said vapors to said raw oil feed, also allow the superheat to be extracted from the said vapors by said raw oil at the earliest possible moment, thus causing condensation of the higher boiling point vapors as quickly as possible 45 and thereby decreasing the velocity of the vapors through the dephlegmator and overcoming the tendency of these vapors to mechanically carry over with the remaining vapors an excessive amount of high boiling point ends.

50 The condensed high boiling point vapors and the unvaporized portion of the raw oil feed continuously pass down through dephlegmator leg 11 through line 12, through cracking coils 5, through line 8 into expansion chamber 9. The dephlegmator may be elevated to a sufficient height to furnish head pressure to force the oil through the cracking tubes, or this oil may be forced through the cracking tubes by interposing a suitable force pump of well known design in line 12.

The expansion chamber is properly insulated 55 so that the amount of heat radiated therefrom can be controlled, but it is preferred to insulate the expansion chamber in such manner that the temperature in the same may be controlled. A portion of the oil in the form of vapors continuously passes through line 10 into the bottom of the dephlegmator and is subjected to the action of the raw oil being fed thereto with the result 60 as already described. The remaining vapors

pass beyond the discharge of the raw oil for further cooling with the further result that more of the higher boiling point fractions are condensed out. This latter condensing action is effected and controlled by taking from the receiver tank 16, through line 23, by pump 24, a sufficient quantity of the cooled pressure distillate and introducing the same into the top of the dephlegmator through spray 26.

Any liquid collected in the expansion chamber 10 is drawn out through lines 27 and 28, through line 29, through cooler 30 and carried through line 31 to any suitable storage or reducing still, the flow being regulated by valves 32 and 33. The usual practice is to use line 27 until the accumulation of carbon in the expansion chamber interferes and then line 28 is used. Additional lines 15 may be provided for drawing off this oil at higher elevations on the expansion chamber.

The manhead 34 is for cleaning the carbon 20 out of the expansion chamber, while manhead 35 is for ventilation and for allowing a man to probe the carbon out of the retort without entering it.

By this process at least 95% of the carbon remaining in the apparatus and produced from 25 cracking the oil will be contained in the expansion chamber and not more than 5% will be contained in the cracking tubes 5, which is of great advantage.

In treating crude oil containing a certain percentage of natural gasoline such natural gasoline 30 contained therein will be vaporized in the dephlegmator and drawn off from the system with the pressure distillate, thus avoiding such gasoline passing through the cracking tubes, hence will 35 allow the cracking tubes to be used for cracking nothing but oil containing no gasoline and of course avoiding taking from the cracking tubes a part of their capacity by passing gasoline through them.

Should the crude oil being treated contain sufficient quantity of natural gasoline, or other products desired as to use more heat to vaporize such gasoline or other desired products than is desired to extract from the vapors in the dephlegmator, 45 then such oil may be preheated to such temperature not in excess of that extracted from the vapors in the dephlegmator. This method may be varied, if desired, by by-passing some of the raw oil directly to the cracking coils through line 4 50 by partly opening valve 2, but in doing this the capacity of the plant is decreased proportionately.

Should the oil being treated contain water 55 when fed over the top such water content will be converted into steam in the dephlegmator by the heat of the vapors in said dephlegmator and such steam passes with the remaining oil vapors over into the pressure distillate tank 16 and may be withdrawn. Should the content of water be such 60 as to take too much heat from the vapors in the dephlegmator then the oil may be preheated in any suitable means before being fed into the dephlegmator, such preheating being sufficient so that the temperature of the oil will be such as 65 not to extract too much heat from the vapors in the dephlegmator. Should it be desired, instead of preheating the oil, sufficient of the oil may be fed direct to cracking coils 5 by regulating the opening of valve 2 and the remaining portion of oil being fed directly into the dephlegmator, the oil going into the dephlegmator not being in excess of amount regulated to take only the desired amount of heat from the vapors in the dephlegmator.

This operation also applies when treating an oil containing both water and natural gasoline, that is, it may be preheated to the proper degree, or such portion of it passed through valve 2 and line 4 to the cracking tubes as is found necessary as above described to keep the desired temperature in the dephlegmator.

In the treatment of oil containing water if the temperature of the vapor in the top of the dephlegmator be maintained too low for the pressure held on the apparatus, the steam generated from this water will be condensed in the dephlegmator and be refluxed back to the cracking tubes and result in the apparatus being water vapor bound. For illustration, the boiling point of water is about 327° F. when maintained at 100 lbs. Temperature, therefore, at the top of the dephlegmator should be maintained sufficiently high to prevent any substantial condensation of the water in the top of the dephlegmator. A very important feature in the operation of this process with oils containing various amounts of water is that there are no sudden variations of pressure.

To give an illustrative run using a gas oil made from mid-continent crude oil and having a gravity of 33° Bé. at 60° F. 500 barrels per day of this raw charging stock is fed into the apparatus through line 1, through valve 3, through line 17 in the dephlegmator through line 18. The vapors entering the bottom of the dephlegmator are approximately 790° F., while the raw oil fed into said dephlegmator is approximately 70° F. The vapors condensed with the raw gas oil and returned pressure distillate fed into the dephlegmator reach a temperature of about 700 to 780° F., and pass down dephlegmator leg 11 through line 12, through coils 5 in which such oil is heated to about 814° F., and are discharged through line 8 into expansion chamber. 200 barrels of residuum are drawn from expansion chamber through lines 27 and 28. The temperature of the vapors at the top of the dephlegmator is about 550° F. and 300 barrels of pressure distillate are taken out through receiving tank 16. This pressure distillate is about 50° Bé. gravity at 60° F. and contains approximately 50% of gasoline boiling point between 100 and 437° F.

For each barrel of raw material fed into the apparatus there are two barrels of reflux condensate condensed from the vapors in the dephlegmator and refluxed back to the cracking tubes for further treatment with the raw oil fed into dephlegmator. Therefore, in the operation there are substantially 500 barrels of raw oil being fed to the apparatus per day, 300 barrels of pressure distillate and 200 barrels of residuum taken therefrom per day, but there are 1,500 barrels of combined raw oil and reflux being passed through the cracking tubes per day. Therefore, there is only 10% of the oil passed through the cracking coils which is converted to gasoline representing 30% of the raw oil being fed in. The pressure distillate produced represents 20% of the total oil passed through the cracking coils and represents 60% of the raw oil being fed in a day.

An important feature of my process is that it is possible to vary the amount of gasoline, pressure distillate and the residuum withdrawn from the system without substantially increasing or decreasing the total combined volume of reflux and raw oil passing through the cracking tubes in a day, or changing the percentage of such total volume that is converted into gasoline. This is accomplished by controlling the temperature in

the dephlegmator through the flow thereto of returned pressure distillate. A pressure distillate may be produced that is rich in gasoline by reducing the quantity of raw oil and simultaneously increasing the flow of returned pressure distillate fed to the dephlegmator, or a larger volume of pressure distillate may be produced by increasing the raw oil and decreasing the returned pressure distillate fed to the dephlegmator. In each instance the temperature of the dephlegmator is so controlled by the flow of returned pressure distillate, a large percentage of which vaporizes therein, that the volume of reflux condensate plus the raw oil charge returned to the heating coil is maintained constant.

I claim as my invention:

1. A continuous process for cracking hydrocarbon oil consisting in passing a constant volume of combined charging oil and reflux condensate through a heating zone wherein it is raised to a cracking temperature, in delivering the heated oil from said heating zone to a reaction zone wherein conversion occurs and from which no unvaporized oil is permitted to return to the heating zone, in passing evolved vapors to a dephlegmating zone wherein they are subjected to reflux condensation by passage in heat interchange relation with the incoming charging oil, in reducing the proportion of charging oil and increasing the proportion of reflux condensate in said constant volume of oil introduced to the heating zone by decreasing the amount of charging oil introduced to the dephlegmating zone and simultaneously returning to the dephlegmating zone an amount of the pressure distillate produced by the process sufficient to compensate for the decreased condensing effect due to the decrease in the amount of charging oil introduced to the dephlegmating zone.

2. A process for treating hydrocarbon oil consisting in continuously introducing a constant volume of combined raw oil and reflux condensate to a heating zone wherein the oil is subjected to cracking conditions of temperature and pressure, in subjecting the evolved vapors to reflux condensation in a dephlegmating zone to supply the reflux condensate in said constant volume of oil, in introducing the charging oil to the dephlegmating zone to flow therethrough in heat interchange relation with the vapors and commingle with the reflux condensate, in lowering the proportion of charging oil to reflux condensate in said constant volume of oil by decreasing the amount of charging oil introduced to said dephlegmating zone and in simultaneously introducing to said dephlegmating zone an amount of the pressure distillate produced by the process sufficient to compensate for the decreased condensing effect due to the decrease in the amount of charging oil introduced to the dephlegmating zone.

3. A conversion process which comprises continuously passing a mixture of charging oil and reflux condensate in a restricted stream through a heating zone and heating the same therein to cracking temperature under pressure, subsequently separating the heated mixture into vapors and residue, fractionating the vapors in a fractionating zone in contact with fresh charging oil for the process to form said mixture for passage through the heating zone, finally condensing the fractionated vapors and introducing resultant final condensate into contact with the vapors undergoing fractionation, and, throughout the normal operation of the process, so correlating

the amount of final condensate introduced to the fractionating zone with the amount of charging oil introduced to the fractionating zone as to maintain substantially constant the volume of the mixture of charging oil and reflux condensate which is formed in the fractionating zone and passed from the latter to the heating zone, the combined cooling action of the charging oil and final condensate introduced to the fractionating zone being sufficient to maintain in said mixture a quantity of reflux condensate at least twice that of the charging oil.

4. In the cracking of hydrocarbon oils, the method which comprises fractionating the cracked vapors in a fractionating zone in contact with a first stream of charging oil for the process to condense insufficiently cracked fractions thereof as reflux condensate, then combining this charging oil and the reflux condensate with a second stream of charging oil, passing the resultant mixture of charging oil and reflux condensate through a heating zone and heating the same

therein to cracking temperature under pressure, separating the heated mixture into vapors and residue and supplying the former to the fractionating zone as said cracked vapors, finally condensing the fractionated vapors and introducing a portion of the resultant final condensate into contact with the vapors in the fractionating zone, the amount of charging oil and final condensate introduced to the fractionating zone being sufficient to form in the latter a volume of reflux condensate at least twice the combined volume of said first and second streams of charging oil, and, throughout the normal operation of the process, so correlating the amount of final condensate introduced into the fractionating zone with the amount of charging oil in said first and second streams as to maintain substantially constant the volume of said mixture of charging oil and reflux condensate passed through the heating zone.

CARLTON P. DURBS.
